ASHTON HEY, OF WAKEFIELD, RHODE ISLAND

MEANS FOR ADJUSTABLY ATTACHING WORSTED COMB BRUSHES TO DABBER FEET

Application filed February 13, 1929. Serial No. 339,681.

This invention relates to a worsted comb brush, the wooden back of which is adjustably secured by bolts (usually two) to a rapidly reciprocating dabber foot. Each bolt 5 extends through a slot in the brush back and is engaged with the dabber foot to clamp the back against the foot, the usual adjustments of the back relative to the foot being permitted by the slots in the back.

10 The invention is embodied in a reinforcing lock washer, one for each bolt, insertible in a socket in the back and adapted to lock the back in any position to which it may be adjusted, to prevent the bolts from turning 15 and splitting and warping the back, and to accomplish other useful results, all as hereinafter described.

Of the accompanying drawings forming a part of this specification,—

20 Figure 1 is a view of the front side of a brush back having reinforcing washers embodying the invention, the brush being removed.

Figure 2 is a view of the rear side of the 25 back showing the dabber foot.

Figure 3 is an edge view of the back and foot.

Figure 4 is a fragmentary perspective view, showing a portion of the back and a socket 30 formed therein for the reception of the reinforcing washer.

Figure 4^a shows a modification of Figure 4.

Figure 5 is a perspective view, showing the washer removed from the back.

35 Figure 6 is a fragmentary section on line 6—6 of Figure 2, a portion of the brush being shown by dotted lines.

Figure 7 is a view similar to a portion of Figure 1, showing a different adjustment of 40 the locking jaws hereinafter described.

The same reference characters indicate the same parts in all of the figures.

12 designates a comb brush back of the general form used in several types of worsted 45 combing machines, the back being of hard wood and oblong, as shown by Figures 1 and 2.

14 designates conventionally the metal foot of a dabber which is rapidly reciprocated by 50 well known means, to reciprocate the back

and the brush 15 attached thereto as usual, the back and brush being reciprocated sideways.

The brush is shown only by Figure 6, by dotted lines. The back is attached to the 55 dabber foot by bolts 16, having heads 17 and clamping nuts 18, engaging threaded portions of the bolts and set up against the foot 14, the bolts passing through slots 19 in the foot. The bolt heads 17 are usually square, 60 and heretofore have been fitted in sockets formed for their reception in the outer side of the back. The wooden walls of said sockets are often cracked and the back warped by the turning of the bolt heads there- 65 in.

My invention obviates this and other objections to direct contact of the bolt-heads with the wooden back, and is carried out as 70 next described.

For each bolt 16 I provide a reinforcing lock washer inserted in a socket 20 (Figure 4) formed for its reception in the front side of the back 12. The body 21 of the washer is formed to closely fit the socket 20, the form 75 of the socket and body being such that the washer body cannot turn in the socket. In the body 21 is formed a recess 22, in the bottom of which is a cross-shaped slot 23, forming two intersecting bolt-receiving ways at 80 right angles to each other. The form and arrangement of said ways is such that either a crosswise or a lengthwise adjustment of the back 12 on the bolt 16 is permitted.

24, 24 designate locking jaws pivoted at 85 to the bottom of the recess 22, and adjustable to the different positions shown by Figures 1 and 7, by swinging the jaws on their pivots. The jaws have longitudinal faces adapted to extend parallel with either of the ways 90 formed by the cross-shaped slot 23, and to bear on opposite sides of the bolt head 17, to lock the bolt against turning in the head, the jaws being backed by wall portions of the recesses, so that they are confined against the 95 bolt head.

The washer recess 22 is provided with angular wall portions 30, having locking faces constituting extensions of the locking faces of the jaws 24, when said jaws are in either of the 100

locking positions shown. The function of said extensions is illustrated by Figure 7, which shows the back adjusted to locate a portion of one of the extensions in position to bear on one of the sides of the bolt head 17.

5 The washer and its jaws may be made of any suitable metal.

The chief advantages of the described improvement are as follows:

10 1st. The bolt head is locked under all possible adjustments of the brush back.

15 2nd. The back is reinforced and maintained out of contact with the bolt head, so that it cannot be cracked or split and warped by strain tending to turn it relative to the bolt.

20 3rd. The brush back is held fast to the daber foot and cannot be pulled off from the bolt. It is well known that if a brush becomes loose or comes off, it is liable to damage the comb circles of a worsted combing machine.

25 4th. The locking of the bolt head permits a considerable saving of time in changing brushes, and prevents any necessity of sawing off the bolt, an operation which might be necessary if the bolt were not positively locked against turning.

30 5th. The washer may be fitted to various makes or forms of comb brush.

The back 12 may be provided in the bottom of the socket 20 with a slot or opening of any form, permitting the described adjustments of the back relative to the bolt 16. As shown by Figure 4, the bottom of the socket is provided with a cross-shaped slot 27, the same coinciding with the cross-shaped slot 23 in the washer. If desired, however, the bottom of the socket may have a straight slot 28, as shown by Figure 4^a, and said slot may extend either crosswise of the back, to permit crosswise adjustment, or lengthwise of the back, to permit lengthwise adjustment. The slot 28, in either case is adapted to cooperate with the lock washer.

45 I claim:

50 1. For use with a worsted comb brush back and a headed bolt attaching the back to a daber foot, a reinforcing lock washer insertible in a socket formed for its reception in the back, and having a recess in its outer side, a bolt-receiving slot in the bottom of said recess, said slot being cross-shaped and forming two intersecting bolt-receiving ways 55 adapted to permit either a crosswise or a lengthwise adjustment of the back on the bolt, and two pivoted locking jaws adjustable in said recess and having faces adapted to extend parallel with either of the slot ways, and 60 to bear on opposite sides of the bolt head to lock the bolt against turning, said jaws being backed by walls of the recess.

65 2. A reinforcing lock washer as specified by claim 1, the washer recess being provided with angular wall portions having locking faces

constituting extensions of the locking faces of the jaws.

In testimony whereof I have affixed my signature.

ASHTON HEY.
